[57] **CLAIM**

The ornamental design for an aerodynamic disk, as shown and described herein.

DESCRIPTION

FIG. 1 is a perspective view of the ornamental aerodynamic disk;

FIG. 2 is a bottom view, of which the top view is a mirror image thereof; and,

FIG. 3 is a side view thereof of which every other side is a mirror image of said side view.

FIG. 1.

FIG. 2.

FIG. 3.
